DESIGN FOR A GAME BOARD

Application filed August 22, 1932. Serial No. 44,666. Term of patent 3½ years.

To all whom it may concern:

Be it known that we, HARRY P. TROENDLY and FRED PAREIRA, citizens of the United States, residing, respectively, at Chicago, in the county of Cook and State of Illinois, and at New York, in the county of New York and State of New York, have invented a new, original, and ornamental Design for a Game Board, of which the following is a specification, reference being had to the accompanying drawing, forming a part thereof.

We claim:

The ornamental design for a game board substantially as shown.

HARRY P. TROENDLY.
FRED PAREIRA.
